(57) **CLAIM**

The ornamental design for a portable multimodal multichannel biosignal meter, as shown and described.

DESCRIPTION

1. Portable multimodal multichannel biosignal meter

1.1 : Front

1.2 : Left

1.3 : Right

1.4 : Back

1.5 : Top

1.6 : Bottom

1.7 : Perspective

This design is used while worn on the user's head, and after measuring biological signals such as brain waves, the signals are transmitted to an external device for analysis or to control objects such as drones based on the signals.
